RECEIVER OR AMPLIFIER

Theo Tillmann, Berlin, Germany, assignor to Telefunken Gesellschaft für Drahtlose Telegraphie m. b. H., Berlin, Germany, a corporation of Germany

Application October 28, 1937, Serial No. 171,423
In Germany October 16, 1936

3 Claims. (Cl. 179—171)

In accordance with the invention the outer resistance of the end tube of a receiver, or amplifier is automatically increased at lower alternating grid voltage at the end tube or at lower average alternating grid potential (for instance owing to volume control) said increase of the outer resistance being so high that the distortions at this lower alternating grid potential are smaller than in the absence of said increase. In this way it is accomplished that for each volume the quality of the reproduction is always the best possible one.

It is known that owing to non-linearity of the working characteristic, distortions appear in the field of the grid voltage-plate current characteristic of the end tube. These distortions depend on the outer resistance when assuming a definite type tube and fixed potentials, this dependence being such in a single grid tube, for instance, that the distortions become smaller at a higher outer resistance. But at a higher outer resistance the range of control in the tube decreases, however, i. e., the power that can be furnished decreases. Hence, hitherto a compromise was necessary between the power that can be furnished and the allowable noise factor.

The invention will be more readily understood from a consideration of the following detailed specification when read in conjunction with the drawing, wherein:

Figure 1 is a curve sheet used to explain certain characteristics of a power output tube operated according to the invention;

Figure 2 illustrates schematically the embodiment of the invention providing adjustments of the transformation ratio of the output transformer; and

Figure 3 is another embodiment of the invention using a variable impedance device to adjust the output impedance.

These conditions become clear from Figure 1. The characteristics show the dependence of the value of the noise factor on the power when considering outer resistances differing in value. In case of a low outer resistance according to the characteristic 1, the noise factor increases greatly at an increase in power (this being shown in exaggeration for the sake of clearness) but the said noise factor is already high at the beginning. In case of a higher outer resistance for instance in accordance with the characteristic 4, the high increase occurs already at lower power, so that the range of control is very much smaller. But within this range the noise factor on the contrary is low.

The invention utilizes this condition in that at high alternating grid potential the operation is carried out with a low outer resistance (for instance in accordance with characteristic 1) and at lower alternating grid potential, with a higher outer resistance (for instance, according to characteristic 4). At a less extended control (alternating grid potential) and at the same outer resistance the noise factor becomes, however, already smaller as seen from the course taken by the characteristics, but when using the invention the noise factor for the respective control is reduced to the lowest possible value. It should be borne in mind, however, that in the case of a single grid tube the volume decreases when the outer resistance is increased, wherefore, at a decrease of the volume the alternating grid potential of the end tube can not be decreased to such an extent as is possible without the use of the invention. However an optimum of small noise factor can be achieved by a suitable relation between the control curves for the alternating grid potential and outer resistance.

In screen grid tubes the conditions are not quite as favorable since in this case there exists at approximately the same power that can be furnished, an outer resistance having a minimum of the noise factor. Since this minimum exists for a higher outer resistance for a lesser control the invention can also be applied in this case.

For practicing the invention various means can be resorted to. For instance, the transformation ratio of the output transformer according to Figure 2 may vary automatically with the control of the volume such that the outer resistance will be increased when the volume control means at the grid of the end tube, for instance, is controlled downwards.

Another possibility resides in that according to Figure 3 a resistor is placed in series to the loudspeaker coil, and which when reducing the volume will be switched in and then increased, whereas at full volume only the loudspeaker coil is in the circuit.

It is also within the scope of the invention that the outer resistance of the end tube automatically sets itself in dependence of the respective amplitude, while in the above examples the dependence is on the average volume taken over a larger period. This would, for instance, be possible in that with the detected audio-frequency the conduction of a resistor placed ahead of the loudspeaker coil would be varied, for instance, by preliminary magnetizing of a choke.

I claim:

1. In an audio frequency current amplifier provided with an electronic tube having a normal direct current component of plate current and 5 provided with an input circuit coupled to a source of signal energy and an output circuit coupled to an external load impedance, the method of controlling the output of the amplifier without altering the direct current resistance of 10 the external plate circuit whereby said normal direct current component of plate current is maintained, which consists in adjusting the amount of coupling between the source and the input of the amplifier, and simultaneously varying 15 the value of the external load impedance in such a direction that the external load impedance is increased as the amount of coupling between the source and the amplifier input is decreased.
2. In signaling apparatus, an electronic tube 20 having a normal direct current component of plate current and provided with an input circuit coupled to a source of signal energy and an output circuit coupled to an external load impedance,

means for controlling the output of said amplifier without altering the direct current resistance of the external plate circuit whereby said normal direct current component of plate current is maintained comprising means for simultaneously varying the amount of coupling between the source and an input circuit of the amplifier and the value of the external load impedance in such a direction that the external load impedance is increased as the amount of coupling between 10 the source and the amplifier input circuit is decreased.

3. The arrangement described in claim 2 characterized by that the output circuit is coupled to the external load impedance through a transformer and by that the value of the external load impedance is varied by varying the ratio of transformation of said transformer, the arrangement being such that the ratio of transformation is decreased as the coupling between the source and 20 the input circuit is decreased.

THEO TILLMANN.
